Application filed November 6, 1899. Serial No. 736,048. Term of patent 3½ years.

To all whom it may concern:

Be it known that I, THOMAS M. HARTMAN, a citizen of the United States, and a resident of the village of Hyde Park, in the county of 5 Hamilton and State of Ohio, have invented and produced a new and original Design for a Display-Rack or Similar Article, of which the following is a specification, reference being had to the accompanying drawings, forming part thereof.

Figure 1 is a front elevation of a structure showing my design. Fig. 2 is an elevation of that edge of the same which faces toward the left hand in Fig. 1.

15 As shown in the drawings, the leading or material feature of my design consists of the elongated structure having the pad-holder A, the panels B and C, and a surmounting ornament E. Each of the panels is bordered 20 by an appropriate molding. The surmounting ornament E, resting upon the basal part D, has the vertical round rods E², having knobs or enlargements and separated by interspaces. There are end ornamental supports E³ E³. Above is a molded flat or table 25 piece E⁴, and on this rests the pyramidal piece E⁵, terminating in the pinnacle E⁶.

The vertical main supporting-structure is indicated by the letter F.

This device of my design is intended to be 30 located near a telephone, but is applicable elsewhere.

Having thus described my invention, what I claim as new, and desire to secure by Letters Patent, is—35 The design for a display-rack or similar article, as herein shown and described.

In testimony whereof I have signed my name to this specification in the presence of two subscribing witnesses.
